UNITED STATES PATENT OFFICE.

SWAN JOHNSON, OF RICHWOOD, WEST VIRGINIA, ASSIGNOR OF ONE-HALF TO JULIA ERLANDSON, OF RICHWOOD, WEST VIRGINIA.

RAIL FASTENER.

Application filed December 6, 1922. Serial No. 605,190.

To all whom it may concern:

Be it known that I, SWAN JOHNSON, a citizen of Sweden, residing at Richwood, in the county of Nicholas and State of West Virginia, have invented certain new and useful Improvements in Rail Fasteners, of which the following is a specification, reference being had to the accompanying drawings.

10 This invention relates to means for fastening rails to ties, and the general object of the invention is to provide a tie and rail engaging means so constructed that the rail is always held down upon the tie and prevented from movement without any danger 15 of the engagement between the rail and tie becoming gradually released.

A further object is to provide a construction of this character which will automatically take up wear and compensate for irregularities in the rails.

Another object is to provide a construction of this character from which the rails cannot work loose as they do upon ordinary ties.

Other objects will appear in the course of the following description.

My invention is illustrated in the accompanying drawings, wherein:

30 Figure 1 is a longitudinal fragmentary sectional view of a tie having my improved rail engaging means applied thereto;

Figure 2 is a like view to Figure 1 but showing the locking wedge in section;

35 Figure 3 is a top plan view of the construction shown in Figure 1;

Figure 4 is a bottom plan view of the wedge and the springs which resiliently urge it in one direction.

40 Referring to these drawings, 10 designates the tie, which may be made of metal or any other suitable material, which is hollow, and which is formed to provide a flat bottom surface 11 and an upper wall 12. The tie is formed with openings 13 on each side of the space upon which the rail A is intended to rest.

• Pivoted within the tie upon transverse shafts or equivalent elements 14 are the rail clamps 15. Each tie may have any number 50 of these rail clamps. I have shown three of these clamps in Figure 3 and the outside of the rail is engaged by two of these clamps, while the inside of the rail is engaged by one of the clamps, thus giving a three-point

engagement. Obviously the arrangement of these clamps may be varied. These clamps are mounted upon the shafts 14 either to rotate therewith or to oscillate independently thereof, and the clamps are so formed as to provide for each clamp a nose 16 which engages over the rail and a tail 17 which extends downward through the corresponding slot 13 and has its under face rounded at 18. The under face of the nose 16 is also slightly rounded so that no matter how much the tail may be elevated the nose will always bear upon and have clamping engagement with the base flange of the rail A.

Disposed within the tie 10 and movable longitudinally upon the bottom wall 11 of the tie is a wedge 19, the upper face of this wedge being inclined upward and toward the middle of the tie and the under sides of the tails 17 of the rail clamps bear upon the upper face of this wedge. This wedge may be of metal or any other suitable material and is provided with side walls and end walls. One of these end walls 20 is perforated for the passage of a rod 21. Extending longitudinally of the wedge are two guide rods 22 disposed one on each side of the rod 21, these guide rods being held in position within the wedge by any suitable means as, for instance, the screws or equivalent members 23. Surrounding each rod is a coiled compression spring 24. There are two of these compression springs and those ends of the springs toward the outer end of the tie bear against the end wall 20 of the wedge.

Slidably mounted upon each rod 22 is a thimble 25, these thimbles being connected by a web 26 so that the thimbles will move together, and the rod 21 is attached to this web 26. Obviously when the rod 21 is pulled to the right in Figure 4, it will compress these springs. The extremity of the rod is connected to a shackle 27 of any suitable character which is engaged over a transverse rod or anchor 28 extending transversely through the tie adjacent the end thereof. It will be obvious, therefore, that the tendency of the springs 24 is to exert a constant push upon the wedge 19 toward the outer end of the tie and obviously as the wedge is pushed toward the right in Figure 2, the wedge-shaped upper face of the wedge will force the tails 17 of the clamps 15 upward and, therefore, force the noses 16 down

upon and into tight clamping engagement with the base flange of the rail.

I do not wish to be limited to the particular form of rail clamp 15 shown in Figure 2, as it is obvious that this may have other forms. I have illustrated in the drawings a rail clamping and supporting member which is preferably used on curves and which is designated generally 29. This member has a relatively long, upwardly inclined nose 30 and a downwardly extending tail 31, the under face of which is rounded and which bears against the upper face of the wedge 19. The nose 30 extends upward 15 and bears against the rail at the intersection of the head with the web of the rail. Obviously any movement of the wedge 19 toward the right in Figure 1 will lift the tail 31 and cause the nose 30 to bear downward, forcing 20 the rail either toward the left or resisting any thrust upon the rail. This rail brace and clamp 29 will be disposed, of course, upon the outside of the rail at curves so as to resist the thrust exerted by the train in 25 turning a curve. This member 29 is to be applied in connection with the clamps 15.

In applying my mechanism to a rail, the hook 27 is disconnected from the rod 28 and the wedge forced inward or toward the 30 middle of the tie. This, of course, will loosen the rail clamps and permit a rail to be inserted beneath said clamps. The hook 27 is then drawn toward the outer end of the tie and this will draw the wedge over 35 until the clamps are engaged and forced against the rail. Further stress placed upon the hook 27 will cause the compression of the springs 24 and these springs will remain under compression, resiliently urging 40 the wedge 19 toward the outer end of the rail. Thus as the rail wears or otherwise tends to become loosened from the tie, the springs will cause the movement of the wedge, which will further force down the 45 noses of the clamps upon the rail and thus the rail will be held at all times in clamped engagement with the tie and there will be no danger of the rail becoming loose by the gradual withdrawal of spikes or the disengagement of fastening devices as there is at 50 the present time. With my construction the clamps are automatically tightened and a continuous pressure is exerted upon these clamps holding them tightly in engagement 55 with the rail. With regard to the combined clamp and brace 29, it is obvious that it will continually exert pressure upon the rail in a contrary direction to that exerted by the thrust of a passing train.

60 It will be seen that this invention does away with the necessity of spiking rails to wooden ties, with all the concomitant evils of spike-killed ties, loose spikes, split ties and the like, and does away with the necessity of continually re-spiking the ties. Fur-

thermore, it will be noted that the noses 16 of the clamps engage over nearly the entire surface of the rail flanges, thus holding the rail much more securely than is possible where the spike merely projects over a portion of the margin of the base flange and resisting tipping strains to an extent not possible with spikes. 70

With my construction there is no possibility of the clamps accidentally becoming 75 disengaged from the rails without a positive breakage of the clamps. The clamps, moreover, are held from breakage by the fact that they operate within the slots in the body of the ties themselves. The wedge 80 cannot slip longitudinally in a direction to release the clamping action and positively holds the clamps engaged with the rail.

While I have illustrated a construction which I believe to be particularly practical, I do not wish to be limited to the details thereof, as it is obvious that these might be varied in many ways without departing from the spirit of the invention. 85

I claim:—

1. A hollow railway tie, a longitudinally movable wedge mounted therein, resilient means urging the wedge in one direction, and rail clamps mounted upon the tie and engaged by said wedge and urged into 95 clamping position by a movement of the wedge in its urged direction.

2. A hollow railway tie, a longitudinally movable wedge mounted therein, resilient means urging the wedge in one direction, 100 rail clamps pivoted upon the tie and having noses engageable over the flanges of a rail, and tails extending down and engaged by the upper face of the wedge.

3. A hollow railway tie having apertures 105 in its upper wall, rail clamps pivoted to said tie and having portions projecting through said apertures and formed to provide noses engageable over the flanges of a rail, the clamps having downwardly and outwardly 110 extending tails, a wedge mounted upon the bottom wall of the tie and against which said tails bear, a spring disposed within the wedge and bearing against that end wall of the wedge toward the outer end of the tie, and means for placing said spring under tension. 115

4. A hollow railway tie, rail clamps pivotally mounted upon the tie and having downwardly and outwardly directed tails and a 120 wedging member movable on the bottom wall of the tie, with the upper face of which the tails engage, and means for resiliently urging said wedging member in a direction to cause it to wedge against the tails of the clamps and force the other ends of the clamps downward against a rail flange.

5. A hollow tie, rail clamps pivotally mounted upon the tie, the upper face of the tie having apertures through which said 130

- clamps extend and each clamp having a nose adapted to rest upon the flange of a rail, a tail extending downwardly and laterally, a hollow wedge resting upon the 5 lower wall of the tie and having its upper face bearing against the tails of said clamps, compression springs disposed within the hollow wedge and bearing against the wall constituting the small end thereof, a member 10 against which the other ends of the springs bear, a rod connected to said member and passing through the small end wall of the wedge whereby the springs may be placed under tension, and means at the 15 outer end of the rod whereby it may be engaged with the tie.
6. A hollow tie, a rail clamp and brace pivotally mounted within the tie and having an upwardly extending nose extending
- through an aperture in the tie and adapted 20 to bear against a rail at the junction of the head with the web thereof, the clamp and brace having a downwardly and laterally extending tail, a wedge resting upon the lower wall of the tie and bearing at its 25 upper face against the under face of said tail, and means for resiliently urging said wedge in a direction to cause the elevation of the tail and the depression of said nose.
7. In a hollow railway tie, rail clamps 30 pivotally mounted upon the tie, the tie having apertures through which the clamps pass, and means within the tie resiliently urging the outer ends of the clamps downward and toward the upper face of the tie. 35

In testimony whereof I hereunto affix my signature.

SWAN JOHNSON.
